(57) **ABSTRACT**

A new and distinct variety of carnation plant characterized
by a distinctive bright red flower color.

1 Drawing Sheet

1

Latin name of genus and species: The present invention
relates to a new and distinct variety of hybrid *Dianthus*
caryophyllus. The varietal denominator of the new variety is
'CFPC Beleza'.

BACKGROUND OF THE INVENTION

The present invention relates to a new and distinct variety
of carnation plant, named 'CFPC Beleza', which is a sport
of the selection 990246 (non-patented), a commercially
available, red colored carnation of the CFPC Adorable
family. The female parent of 990246 is identified as 'CFPC
selena' (U.S. Plant Pat. No. 11,899), color crimson; the male
parent in an unknown seedling. The primary objective of the
controlled breeding program was to extend the color range
of the CFPC Romance series to include a bright red flower.
The closest commercial cultivar in color to the new cultivar
of which I am aware is the carnation 'CFPC Tiara' (U.S.
Plant Pat. No. 14,797). Tiara is a shorter cultivar in the
Adorable series.

SUMMARY OF THE INVENTION

Among the novel characteristics possessed by the new
variety which distinguishes it is a distinctive bright red
flower color, which retains its color without fading. When
grown in 4½ inch pots in Salinas, Calif., plant diameter
averages about 6½ inches. Pinched plants are about 7½ to
7¾ inches tall and flowers are about 1¾ inches average
diameter with a crown higher than about ⅝ inches. Foliage
is about 4 inches long and about ⅝ inches wide.

Asexual reproduction and flowering of this new cultivar
by side shoot cuttings as performed in Salinas, Calif., shows
that the foregoing and other distinguishing characteristics
come true to form and are established and transmitted
through succeeding propagations.

COMPARISON TO PARENTS

'CFPC Beleza' is characterized by a distinctive bright red
color flower, which retains its color without fading. The
flower is brighter than that of 990246, a red colored carna-

2

tion of the CFPC Adorable family, of which 'CFPC Beleza'
is a sport. The female parent of 990246, CPFC Selena, has
a crimson flower; the male parent of 990246 is unknown.

5 BRIEF DESCRIPTION OF ILLUSTRATIONS

The accompanying photographic illustration shows a
typical specimen of the new variety in color as nearly true
as it is reasonably possible to make in a color illustration of
this character.

15 DESCRIPTION OF THE NEW VARIETY

Referring now specifically to the new and distinct variety
15 of carnation plant the following is a detailed description of
'CFPC Beleza', approximate age 121 days, with color
description where indicated by reference to The Royal
Horticultural Society Colour Chart, except where common
terms of color definition are employed.

20 The new variety of carnation plant as herein disclosed
may vary in slight detail due to climatic, soil and cultural
conditions under which the variety may be grown, the
present description being of the variety as grown at Salinas,
Calif.

25 The new variety is a greenhouse-type plant, suitable for
production as a pot spray.

Plant:

30 *Height*.—About 7½–7¾ inches tall.

Form.—Herbaceous.

Growing habit.—Semi-upright.

Blooming habit.—As a spray when grown in a pot;
blooming time, approximately 110 days.

Shelf life.—Approximately 21 days in bloom.

Blooming season.—Year round.

Rooting time.—About 18 days.

Breaking action.—Good.

Mutation prone.—No.

35 *Disease resistance*.—Resistant to *Fusarium oxysporum*
and *Fusarium graminearum*.

Foliage:

Color.—Upper side: near 137A; lower side: near 139B.
Size.—Length: about 4 inches; width: about $\frac{5}{16}$ inches.
Quantity.—Numerous.
Shape.—Lanceolate.
Texture.—Smooth.
Ribs.—Central keel.
Arrangement.—Bilateral along stem.
Stem color.—Near 138D.

Bud:

Shape.—Ovoid.
Color.—Near 137C.
Size.—Length: about 1 inch; diameter: about $\frac{7}{16}$ inches.

Calyx:

No. of lobes (sepals).—Five.
Size.—Length: about $\frac{1}{4}$ inches; width: about $\frac{3}{16}$ inches.
Color.—Outside: near 139C; inside: near 138D.

Bloom:

Shape.—Rounded.
Size.—Diameter (average): about $1\frac{3}{4}$ inches; depth (average): about $\frac{5}{8}$ inches.
Borne.—As a spray.
Color.—General tonality: red; Upper side: near 46B; Lower side: near 46D; Center: near 45B; Outer petals: near 46B; Base: near 147D.
Permanence.—Dry up on receptacle.
Keeping quality.—Good.
Fragrance.—Slight.

Petalage:

Number.—Twenty six.
Outer petals.—Length: about $1\frac{11}{16}$ inches; Width: about $\frac{11}{16}$ inches.
Central petals.—Length: about $1\frac{1}{2}$ inches; Width: about $\frac{1}{4}$ inches.
Texture.—Smooth.
Appearance.—Shiny.
Form.—Fan-shaped.

Reproductive organs:

Stamen.—None (male sterile).
Anthers.—None.
Filaments.—None.
Pistil.—Length: $1\frac{3}{8}$ inches; Number: one (trilobed).
Color: White (whiter than 155D).
Stigma.—Number: 3; *Color*: White (whiter than 155D).
Fertility.—Male: sterile.
Ovary.—Shape: conical; *Color*: base near 145D, body near 145A, apex near 145A.
Size.—Length: about $\frac{5}{16}$ inches; Width: about $\frac{1}{4}$ inches.

I claim:

1. A new and distinct variety of carnation plant identified as 'CFPC Beleza', substantially as shown and described.
